ABSTRACT OF THE DISCLOSURE

N-substituted acylamidosulfenyl chlorides of the formula

wherein R is an alkyl group of from 1 to 10 carbon atoms or cycloalkyl group of from 3 to 10 carbon atoms, the alkyl or cycloalkyl groups being optionally substituted with halogen atoms and R¹ is hydrogen, alkyl of from 1 to 10 carbon atoms or cycloalkyl of from 1 to 10 carbon atoms, the alkyl or cycloalkyl groups being optionally substituted with halogen atoms; with the proviso that R and R¹ may be joined to form a linear alkylene radical of 3 to 5 carbon atoms which is bound to the carbonyl and nitrogen to form a ring. The compounds are prepared by reacting N-substituted carboxamines with sulfur dichloride. The N-substituted acylamidosulfenyl chlorides are useful intermediates in the preparation of pesticides.

FIELD OF THE INVENTION

The present invention is directed to N-substituted acylamidosulfenyl chlorides and their method of preparation. The subject acylamidosulfenyl chlorides are useful intermediates in the preparation of pesticides.

DESCRIPTION OF THE INVENTION

The N-substituted acylamidosulfenyl chlorides of the present invention may be represented by the formula:

wherein R is alkyl of from 1 to 10 carbon atoms, alkyl of from 1 to 10 carbon atoms substituted with halogen of atomic number 17 to 35 (chlorine or bromine), cycloalkyl of from 3 to 10 carbon atoms or cycloalkyl of from 3 to 10 carbon atoms substituted with halogen atoms of atomic number 17 to 35; R¹ is hydrogen, alkyl of 1 to 10 carbon atoms, alkyl of 1 to 10 carbon atoms substituted with halogen atoms of atomic number 17 to 35, cycloalkyl of 3 to 10 carbon atoms or cycloalkyl of 3 to 10 carbon atoms substituted with halogen atoms of atomic number 17 to 35; with the proviso that R and R¹ may be joined to form a linear alkylene radical of 3 to 5 carbon atoms which is bound to the carbonyl and nitrogen to form a ring. Preferably the haloalkyl radical or halo-cycloalkyl radical will contain 1 to 4 halogen substituents, more preferably 1 to 2 halogen substituents.

Preferably R is alkyl of 1 to 6 carbon atoms, alkyl of 1 to 6 carbon atoms substituted with 1 to 4 halogen atoms of atomic number 17 to 35, preferably 1 to 2 halogen atoms of atomic number 17 to 35, cycloalkyl of 3 to 6 carbon atoms or cycloalkyl of 3 to 6 carbon atoms substituted with 1 to 4 halogen atoms of atomic number 17 to 35, preferably 1 to 2 halogen atoms of atomic number 17 to 35; and R¹ is hydrogen, alkyl of 1 to 6 carbon atoms, alkyl of 1 to 6 carbon atoms substituted with 1 to 4

2

halogen atoms of atomic number 17 to 35, preferably 1 to 2 halogen atoms of atomic number 17 to 35, cycloalkyl of 3 to 6 carbon atoms of cycloalkyl of 3 to 6 carbon atoms substituted with 1 to 4 halogen atoms of atomic number 17 to 35, preferably 1 to 2 halogen atoms of atomic number 17 to 35.

Still more preferably R is alkyl of 1 to 4 carbon atoms or alkyl of 1 to 4 carbon atoms substituted with 1 to 2 halogen atoms of atomic number 17 to 35, preferably 1 to 2 chlorine and R¹ is hydrogen or alkyl of 1 to 4 carbon atoms or alkyl of 1 to 4 carbon atoms substituted with 1 to 2 halogen atoms of atomic number 17 to 35, preferably 1 to 2 halogen atoms of atomic number 17 to 35.

R and R¹ may be joined to form a linear alkylene radical of 3 to 5 carbon which is bound to the carbonyl and nitrogen to form a ring. The acylamidosulfenyl chlorides in which R and R¹ are joined to form a ring with the carbonyl and nitrogen may alternatively be represented by the formula:

wherein R² is a linear alkylene of 3 to 5 carbon atoms.

Representative alkyl groups which R and R¹ above may represent are methyl, ethyl, n-propyl, isopropyl, n-butyl, isobutyl, pentyl, hexyl, heptyl, octyl, nonyl, decyl, 2-methylbutyl, 3-methylphenyl, cyclopentyl, cyclohexyl, cyclooctyl, chloromethyl, 2-chloroethyl, 3-chloropropyl, 4-chloroamyl, 6-chlorohexyl, 2,6-dichlorocyclohexyl, 2,6-dibromocyclohexyl, 3-bromocyclohexyl, bromomethyl, 2-bromoethyl, 3-bromopropyl, etc.

Alkyl radicals which R and R¹ taken together or R² may represent are propylene, butylene and amylene.

Typical acylamidosulfenyl chlorides represented by the above formula are: N-methyl formamidosulfenyl chloride, N-ethyl formamidosulfenyl chloride, N-propyl formamidosulfenyl chloride, N-butyl formamidosulfenyl chloride, N-chloromethyl formamidosulfenyl chloride, N-2-chloroethyl formamidosulfenyl chloride, N-2-chloropropyl formamidosulfenyl chloride, N-bromomethyl formamidosulfenyl chloride, N-cyclopropyl formamidosulfenyl chloride, N-cyclobutyl formamidosulfenyl chloride, N-cyclohexyl formamidosulfenyl chloride, N-methyl acetamidosulfenyl chloride, N-ethyl acetamidosulfenyl chloride, N-propyl acetoamidosulfenyl chloride, N-butyl acetamidosulfenyl chloride, N-methyl chloroacetamidosulfenyl chloride, N-methyl bromoacetamidosulfenyl chloride, N-methyl propionamidosulfenyl chloride, N-ethyl propionamidosulfenyl chloride, N-chloromethyl propionamidosulfenyl chloride, N-methyl 3,3-dichloropropionamidosulfenyl chloride, N-methyl-2,3-dibromopropionamidosulfenyl chloride, N-butyl propionamidosulfenyl chloride, N-methyl butyramidosulfenyl chloride, N-ethyl butyramidosulfenyl chloride, N-cyclohexyl butyramidosulfenyl chloride, N-isopropyl butyramidosulfenyl chloride, N-methyl valeramidosulfenyl chloride, N-methyl 3,4,5-trichlorovaleramidosulfenyl chloride, N-chloromethyl caproamidosulfenyl chloride, N-ethyl 6,7-dichloroanthamidosulfenyl chloride, N-methyl caprylamidosulfenyl chloride, N-methyl cyclohexanoamidosulfenyl chloride, N-methyl 2-chlorocyclopentanoamidosulfenyl chloride, N-thiocloro pyrrolidone, N-thiocloro piperidone, N-thiocloro caprolactam.

The acylamidosulfenyl chloride of this invention may be prepared by reacting sulfur dichloride with a mono-alkylated amide or a lactam. This reaction is illustrated by the following chemical equation:

3

wherein R and R¹ are as previously defined. It is desirable to use stoichiometric proportions of the reactants or an excess of the sulfur dichloride reactant, up to, e.g. 4:1 mole ratio.

The reaction temperature in general is not critical and will usually be in the range of -50 to 100° C., preferably -20 to 60° C. Likewise the pressure is not critical and will usually be atmospheric or autogenous. Reaction time will generally be from 1/4 hr. to 5 hours.

The reaction will generally be carried out in the presence of an inert solvent such as dichloromethane, diethyl ether, tetrahydrofuran, dimethylformamide, dioxane, acetonitrile, and the like. Generally each of the reactants will be admixed separately with a solvent and then the mixture containing the amide and preferably a hydrogen halide acceptor will be added slowly with stirring to the mixture containing the sulfur dichloride. The amount of solvent should be equal to or up to five times the weight of the sulfur dichloride. Likewise the solvent for the amide-halide acceptor mixture should be equal to or up to five times the weight of both.

The sulfur dichloride should be added in high purity, for example greater than 98% purity. It is frequently desirable to have a small amount of an inhibitor such as tributyl phosphate or triethylphosphate present with the sulfur dichloride in order to maintain the high purity.

The reaction is preferably carried out in the presence of a mild hydrogen halide acceptor. At least stoichiometric amounts of acceptor should be used. Soluble tertiary amines such as pyridine and trialkylamines, e.g., triethylamine and tributylamine are preferred.

The acylamidosulfenyl chlorine can generally be recovered from the reaction mixture by stripping any excess sulfur dichloride, filtering off the salt formed between the hydrogen halide acceptor and the HCl, evaporating the solvent and the product purified as by distillation or recrystallization.

The compounds of the present invention are useful intermediates in the preparation of pesticides. Thus the compounds of the present invention may be used to produce aryl N-(N'-alkylacylamidothio)-N-alkyl carbamates which have pesticidal, particularly insecticidal activity. These compounds are prepared by the reaction of an N-alkyl acylamidosulfenyl chloride with an aryl N-alkyl carbamate. Thus for example, m-sec-butylphenyl N-(N'-methylacetamidothio)-N-methyl carbamate may be prepared by reacting N-methyl acylamidosulfenyl chloride of the present invention with m-sec-butylphenyl N-methyl carbamate according to the general chemical reaction scheme:

The present invention can be more fully understood by reference to the following examples.

Example 1

N-methyl formamidosulfenyl chloride was produced by the reaction of N-methylformamide and sulfur dichloride in the presence of dichloromethane and triethylamine.

80 g. of SCl₂ was placed in a flask with 150 ml. of dichloromethane. The mixture was chilled in an ice bath and 23 g. of N-methylformamide and 40 g. of triethylamine dissolved in about 100 ml. of dichloromethane were added dropwise.

The triethylamine hydrochloride salt formed between the halogen halide acceptor and HCl was filtered off and the dichloromethane evaporated. The product was taken

4

up in petroleum ether and the remaining salt filtered. The petroleum ether was then evaporated and the product distilled. The fraction boiling at 39° C./05 mm. was analyzed. This analysis showed:

Calculated (percent): Cl, 28.23; S, 25.5. Found (percent): Cl, 31.88; S, 26.60.

The proton magnetic resonance spectra and infrared spectra further confirmed the structure.

Example 2

N-methyl acetamidosulfenyl chloride was prepared as follows:

268 g. of freshly distilled sulfur dichloride stabilized with tributyl phosphate and 500 ml. of dichloromethane was cooled in a Dry Ice bath to -10° C. Then a mixture of 142 g. of N-methylacetamide and 154 g. of pyridine in 200 ml. of dichloromethane was added with stirring over a period of 5 hours. The temperature was maintained between -10° and 0° C. Stirring was continued for one hour after addition at a temperature of 0° C. The solid residue was removed by filtration, dichloromethane was evaporated and the product taken up in hexane which was then evaporated. The liquid product was analyzed. Elemental analysis was as follows:

Calculated (percent): S, 22.98; Cl, 25.42. Found (percent): S, 23.04; Cl, 27.35.

Example 3

N-methyl chloroacetamidosulfenyl chloride was prepared as follows:

134 g. of freshly distilled SCl₂ stabilized with tributylphosphate in 300 ml. of dichloromethane was cooled in a Dry Ice bath to -10° C. A mixture of 100 g. of N-methylchloroacetamide, 73.5 g. of pyridine and 150 ml. of dichloromethane was slowly added. Temperature was maintained between -10° and 0° C. during the addition time of 45 minutes. The mixture was then allowed to warm to room temperature over about 2 hours, then 250 ml. of hexane was added and the mixture again cooled to 0° C. The solid residue was removed and the solution was stripped of hexane to give a thick dark oil. N-methyl chloroacetamidosulfenyl chloride was recovered by distillation and had a boiling point of 68° C. at 1.5 mm. Nuclear magnetic resonance analysis and infrared analysis helped confirm the structure.

Example 4

Preparation of N-ethyl formamidosulfenyl chloride:

To a solution of 176 g. of freshly distilled sulfur dichloride containing a small amount of tributyl phosphate stabilizer, in 250 ml. of dichloromethane at -10° C. There was added over a period of 1 hour a solution of 100 g. of N-ethyl formamide, 108 g. of pyridine and 200 ml. of dichloromethane. The resulting mixture was stirred for an additional hour. Then 200 ml. of hexane was added and the soluble residue removed by filtration at 0° C. The filtrate was evaporated under reduced pressure to give 173 g. of an oily liquid. This material was distilled and the fraction having a boiling point of 25-30° C. at 0.5 mm. pressure was taken as the product. An NMR spectra was consistent with the structure assigned. Elemental analysis gave the following results:

Calculated (percent): S, 22.97; Cl, 25.40. Found (percent): S, 22.58; Cl, 25.85.

Example 5

Preparation of N-thiocloro pyrrolidone:

Freshly distilled sulfur dichloride, 20.6 g., was dissolved in 100 ml. of dichloromethane containing a small amount of tributyl phosphate stabilizer. To this solution there was added a solution of 8.5 g. of pyrrolidone and 10.2 g. of triethylamine, dissolved in 100 ml. of dichloromethane. The resulting mixture was filtered, and the filtrate was concentrated by evaporation under reduced pressure. The thereby formed precipitate was removed by filtration, and

the oily liquid product was analyzed in the infrared. There was a medium strong peak between 18 and 19 μ . Distillation should be avoided, or carefully performed, to prevent violent decomposition of the N-trichloro pyrrolidone.

As will be evident to those skilled in the art, various modifications on this invention can be made or followed, in the light of the foregoing disclosure and discussion, without departing from the spirit or scope of the disclosure or from the scope of the following claims.

I claim:

1. Compound of the formula

wherein R is alkyl of 1 to 6 carbon atoms, alkyl of 1 to 6 carbon atoms substituted with 1 to 2 halogen atoms of atomic number 17 to 35, cycloalkyl of from 3 to 6 carbon atoms or cycloalkyl of from 3 to 6 carbon atoms substituted with 1 to 2 halogen atoms of atomic number 17 to 35; R¹ is hydrogen, alkyl of 1 to 6 carbon atoms, alkyl of 1 to 6 carbon atoms substituted with 1 to 2 halogen atoms of atomic number 17 to 35, cycloalkyl of 3 to 6 carbon atoms or cycloalkyl of 3 to 6 carbon atoms substituted with 1 to 2 halogen atoms of atomic number 17 to 35; with the proviso that R and R¹ may be joined to form a linear alkylene radical of 3 to 5 carbon atoms which is bound to the carbonyl and nitrogen to form a ring.

2. Compound of claim 1 wherein R is alkyl of 1 to 4 carbon atoms or alkyl of 1 to 4 carbon atoms substituted with 1 to 2 chlorine atoms; R¹ is hydrogen, alkyl of 1 to 4 carbon atoms or alkyl of 1 to 4 carbon atoms substituted with 1 to 2 chlorine atoms.

3. Compound of claim 2 wherein R is methyl or ethyl and R¹ is hydrogen, methyl or chloromethyl.

4. Compound of claim 1 wherein R and R¹ are joined to form a linear alkylene radical of 3 carbon atoms.

5. The method of preparation of the compound of the formula

- 5 wherein R is alkyl of 1 to 6 carbon atoms, alkyl of 1 to 6 carbon atoms substituted with 1 to 2 halogen atoms of atomic number 17 to 35, cycloalkyl of from 3 to 6 carbon atoms, cycloalkyl of from 3 to 6 carbon atoms substituted with 1 to 2 halogen atoms of atomic number 17 to 35; R¹ is hydrogen, alkyl of 1 to 6 carbon atoms, alkyl of 1 to 6 carbon atoms substituted with 1 to 2 halogen atoms of atomic number 17 to 35, cycloalkyl of 3 to 6 carbon atoms, cycloalkyl of 3 to 6 carbon atoms substituted with 1 to 2 halogen atoms of atomic number 17 to 35;
- 10 15 with the proviso that R and R¹ may be joined to form a linear alkylene radical of 3 to 5 carbon atoms which is bound to the carbonyl and nitrogen to form a ring, which comprises reacting in the presence of a hydrogen halide acceptor a monoalkylated amide or lactem with 20 sulfur dichloride according to the reaction:

- 25 wherein R and R¹ are as defined above.
